UNITED STATES PATENT OFFICE

2,480,303

HOIST

Ford Pennell, Webster Groves, Mo., assignor to
Jane Booth Pennell, Webster Groves, Mo.

Application June 28, 1946, Serial No. 680,144

10 Claims. (Cl. 254—167)

1

The invention relates to hoists and has as an object to provide a hoist which is compact, simple in design, light in weight and easy to manufacture.

Some hoists used heretofore employed a ratchet and pawl for step by step upward movement of the load and a braking mechanism for controlling downward movement of the load. The brake locked tightly during upward movement of the load making it difficult to start the load downwardly.

To overcome this difficulty other hoists used heretofore employed a ratchet wheel and a roller chain sprocket, each engaged by a separate pawl, to raise and lower the load. Hoists of this kind were limited to the use of a roller chain, flexible in one plane only, to mesh with the sprocket and support the load.

Another object of the invention is to overcome this limitation by using a plurality of pawls in engagement with a ratchet wheel to raise and lower the load and to utilize a welded coil wire chain, rope, or cable, flexible in all planes, in engagement with a pocket wheel or drum to support the load. The term, "pocket wheel" is a descriptive word used by the trade to designate a wheel with depressions in the periphery to engage the links of a welded coil wire chain so that one may drive the other to transmit power.

Another object of the invention is to provide ready access to the pawl operating springs and without substantial disassembly of the device.

These and other detail objects of the invention, as will appear below, are attained by the structure shown in the accompanying drawings, which structure is intended to be illustrative and not exclusive of other arrangements embodying the general inventive principle. In these drawings:

Figure 1 is a side elevation of a hoist constructed according to the invention, part of the handle being broken away.

Figure 2 is a transverse vertical section drawn to enlarged scale and taken approximately on line 2—2 of Figure 1.

Figure 3 is a transverse section taken approximately on lines 3—3 of Figures 1 and 4 and drawn to the same scale as Figure 2.

Figure 4 is a longitudinal vertical section drawn to an enlarged scale and taken approximately on line 4—4 of Figure 2 showing the mechanism in one position when lowering the load.

Figures 5 and 6 are views similar to Figure 4 drawn to a smaller scale and showing the hoist

mechanism in other positions during lowering movement.

Figure 7 is a view similar to Figure 5 showing the hoist mechanism adjusted to raise a load.

5 Figure 8 is a view similar to Figure 5 showing the operating handle in rear position.

Figure 9 is a detail perspective view of a ratchet wheel engaging pawl.

10 Figure 10 is a perspective of the reversing handle and associated parts and

Figure 11 is a detail of a cam for providing step by step downward movement of the load.

The hoist comprises housings 1 and 2 fastened rigidly together and having aligned bearings 3

15 and 4 rotatably supporting a shaft 5. A pocket wheel 6 formed integral with shaft 5 and a ratchet wheel 7 keyed to shaft 5 rotate therewith. Pocket wheel 6 has a peripheral zone for mounting a load supporting element, such as a flexible

20 link chain 38, and ratchet wheel 7 has teeth spaced axially from the zone. A bushing 8 is keyed to shaft 5 and holds ratchet wheel 7 against a shoulder 9 on the shaft. A washer 10, attached to the end of shaft 5 by a screw 11 threaded there-

25 in, presses against bushing 8. A cam 12 is mounted rotatably on shaft 5 between ratchet wheel 7 and bearing 4 and an operating handle 13 pivots on bushing 8 adjacent ratchet wheel 7 opposite cam 12 and is held on shaft 5 by washer 10. Angular movement of handle 13 is limited to

30 slightly more than 180° by lugs 14 and 15 on the handle engaging a stop 16 on housing 2 (Figure 4).

Flexible link chain 38 for supporting the load 35 rides on and meshes with pocket wheel 6, and a guide 39 attached rigidly to housing 2 prevents chain 38 from jamming pocket wheel 6. At one end of chain 38 is a hook 40 to receive the load and at the opposite end is a stop 41 to prevent

40 the end of chain 38 from running off of pocket wheel 6. Hook 40 is mounted rotatably on a cylindrical member 54 to permit angular movement of the load. A hook 42 for supporting the hoist is rotatable in housings 1 and 2 and includes a boss

45 52 swiveling in a recess formed by the housings to permit angular movement of the hoist about its vertical axis.

Mounted pivotally on a pin 51 in housing 2 is a load pawl 17 urged into engagement with the

50 teeth of ratchet wheel 7 by a curved spring 18 having one end engaging pawl 17 at a slot 55 and the other end attached to a boss 19 on housing 2. A pawl 21 is attached pivotally to handle 13 by a pin 20 and is urged into engagement with the teeth of ratchet wheel 7 by a spring 22 abut-

ting pawl 21 and positioned in a recess 23 in a part 24 attached to handle 13. Load pawl 17 and handle pawl 21 are substantially as wide as the combined width of ratchet wheel 7 and cam 12, and ratchet wheel engaging face 25 of handle pawl 21 is recessed as shown at 26 in Figure 9, a distance equal to the thickness of cam 12, and to a depth sufficient to clear cam 12. A trigger 27, substantially as wide as cam 12, is mounted pivotally on a pin 33 in a groove 28 in pawl 21. A spring 48 urges trigger 27 toward cam 12 and into engagement with a boundary of groove 28.

Cam 12 has a radial load pawl engaging face 29, radial trigger engaging faces 30 and 31, and a radially extending arm 32. A spring 33 having one end attached to arm 32 and the other end attached to a pin 34 on housing 2 urges cam 12 in a counter-clockwise direction (Figures 4 to 8). Movement of cam 12 in this direction is limited by a lug 35 (Figures 3 and 10) mounted eccentrically on a shaft 36 supported rotatably in housings 1 and 2 and operated through an angle of approximately 180° by a reversing handle 37 positioned exteriorly of housing 1.

When the load is suspended from the hoist and is neither being raised nor lowered, load pawl 17 normally sustains the load by engaging ratchet wheel 7 to prevent rotation of pocket wheel 6.

When raising the load reversing handle 37 is adjusted to point upwardly as shown in broken lines in Figure 1, lug 35 being rotated 180° (Figure 7) to move cam 12 to non-operative position. Load pawl 17, handle pawl 21 and ratchet wheel 7 operate as an ordinary ratchet mechanism to raise and hold the load in any desired position.

To raise the load, operating handle 13 is moved from a substantially horizontal position (Figure 7) downwardly in a counter-clockwise direction whereby handle pawl 21 engages ratchet wheel 7, relieving load pawl 17 of the load, and rotates shaft 5, pocket wheel 6 and associated parts in a counter-clockwise direction to raise hook 40, load pawl 17 sliding over ratchet wheel 7. Handle 13 is moved in this direction until load pawl 17 rides past the tooth on ratchet wheel 7 next to the one previously engaged thereby. This is noticeable by a sharp click. Then handle 13 is moved in a clockwise direction, the load being sustained by load pawl 17, until handle pawl 21 passes the tooth on ratchet wheel 7 previously engaged by load pawl 17, then handle 13 is moved under load in a counter-clockwise direction and the sequence of operation described above is repeated. The load is raised step by step by a pumping motion of handle 13 producing a straight ratchet action of pawls 17 and 21 on ratchet wheel 7.

When lowering the load reversing handle 37 is adjusted to point downwardly as shown in solid lines in Figure 1, rotating lug 35 through an angle of 180° (Figures 4, 5 and 6) to release cam 12 which is urged by spring 33 into engagement with load pawl 17 or trigger 27 of handle pawl 21 to alternately disengage pawls 17 and 21 from ratchet wheel 7 as the pawls are freed of the load by movement of handle 13. The force exerted by spring 33 through cam 12 on pawls 17 and 21 is sufficient to disengage the pawls from ratchet wheel 7 when the pawls are free of the load, and insufficient to disengage pawls 17 and 21 from ratchet wheel 7 when the pawls are sustaining the load.

To lower the load, operating handle 13 is moved manually downwardly slightly in a counter-clockwise direction until handle pawl 21 and handle 13 relieve load pawl 17 of the load, where-

upon cam 12 is rotated by spring 33 in a counter-clockwise direction and moves load pawl 17 out of contact with ratchet wheel 7 (Figure 4). Operating handle 13, carrying the load, then is moved manually upwardly in a clockwise direction to rotate pocket wheel 6 and lower hook 40. Near the end of clockwise movement of handle 13, trigger 27 of handle pawl 21 engages radial face 30 of cam 12 and moves cam 12 out of engagement with load pawl 17, whereupon load pawl 17 pivots into contact with ratchet wheel 7 (Figure 5) and engages the next tooth as it moves into registry therewith. Handle pawl 21, relieved of the load, is pivoted by cam 12 out of engagement with ratchet wheel 7 as the cam is rotated slightly in a counter-clockwise direction by spring 33 (Figure 6). Operating handle 13 then is moved manually in a counter-clockwise direction, cam 12 holding handle pawl 21 out of engagement with ratchet wheel 7 until handle pawl 21 passes the tooth on ratchet wheel 7 previously engaged thereby, whereupon trigger 27 moves out of engagement with cam 12 (which engages load pawl 17) and handle pawl 21 slides on ratchet wheel 7 until it moves into registry with and engages the next tooth, whereupon handle 13 again takes the load from load pawl 17, as described above. The load is lowered step by step by a pumping motion of handle 13 similar to the motion used for raising the load.

Lug 14 on handle 13 and stop 16 on housing 2 are arranged to prevent interference between load pawl 17 and handle pawl 21, and to prevent engagement of radial trigger engaging face 30 of cam 12 and trigger 27 while raising the load. Lug 15 on handle 13 is arranged to cooperate with stop 16 to prevent interference between handle pawl 21 and arm 32 of cam 12.

Chain 38 may be free-wheeled on pocket wheel 6 to raise hook 40 with or without load by pulling downwardly on chain 38 at stop 41 (Figure 1), whereupon the chain rotates pocket wheel 6, shaft 5 and associated parts in a counter-clockwise direction (Figures 4 to 8) and load pawl 17 and handle pawl 21 slide on ratchet wheel 7. Chain 38 may be free-wheeled on pocket wheel 6 to lower hook 40 without load when reversing handle 37 is in lowering position, by depressing a lever 43 mounted pivotally on handle 13 and pulling downwardly on hook 40 (Figure 1). Lever 43 is connected to one end of a rod 44 which is positioned longitudinally of handle 13 and has a hook 45 at the other end connected to a spring 46. Spring 46 is attached to a lug 47 on handle pawl 21. When lever 43 is pressed toward handle 13, rod 44 and spring 46 are moved longitudinally in handle 13 and pivot handle pawl 21 away from ratchet wheel 7. With reversing handle 37 in load lowering position, load pawl 17 is held out of engagement with ratchet wheel 7 by cam 12. With both load pawl 17 and handle pawl 21 free of engagement with ratchet wheel 7, chain 38 can be freewheeled on pocket wheel 6 in either direction. A compression spring 49, encircling rod 44, returns lever 43 and associated parts to original position when lever 43 is released from manual engagement. The tension exerted by spring 46 when lever 43 is depressed is sufficient to disengage handle pawl 21 from ratchet wheel 7 only when handle pawl 21 is not sustaining the load. When handle pawl 21 sustains the load and lever 43 is depressed, spring 46 stretches and absorbs movement of rod 44 without disengaging handle pawl 21 from ratchet wheel 7, thus preventing accidental dropping of the load.

Chain 38 also may be free-wheeled on pocket wheel 6 to lower hook 40 without load when reversing handle 37 is in lowering position simply by moving handle 13 to substantially vertical position and pulling downwardly on hook 40. With handle 13 in this position trigger 27 engages the circumference 56 of larger diameter of cam 12 adjacent radial face 31, and handle pawl 21 is moved out of engagement with ratchet wheel 7. Thus handle 43 and associated parts linking it with pawl 21 may be omitted and the hoist will perform substantially the same function.

At times it may be convenient to operate handle 13 from the rear or right-hand side of the hoist as shown in Figure 8. The load may be raised or lowered with the handle in this position substantially as described above, except that in lowering the load radial face 31 of cam 12 instead of radial face 30 engages trigger 27 to move handle pawl 21 out of engagement with ratchet wheel 7 after the load is transferred from handle pawl 21 to load pawl 17 as described above.

Handle 13 preferably is moved from front to rear operating position, while load pawl 17 sustains the load, by depressing lever 43 to disengage handle pawl 21 from ratchet wheel 7 and moving the handle in counter-clockwise direction to rear operating position. Or handle 13 may be moved from front to rear operating position by merely rotating the handle in a counter-clockwise direction beyond the limits of ordinary pumping movement. If the hoist is not loaded, handle pawl 21 is moved out of engagement with ratchet wheel 7 when trigger 27 engages the circumference 56 of larger diameter of cam 12. If the hoist is loaded, trigger 27 pivots against pressure of spring 48 without disengaging handle pawl 21 from ratchet wheel 7 as the trigger engages circumference 56 of cam 12 and handle 13 is moved under load from one position to the other raising the load slightly.

Operating handle 13 may be moved from rear to front operating position merely by rotating the handle in a clockwise direction. As the handle is rotated, the load is sustained by load pawl 17 and when trigger 27 engages radial face 31 of cam 12 handle pawl 21 pivots out of contact with ratchet wheel 7 and trigger 27 slides over circumference 56 of cam 12.

A hoist constructed according to the invention as described above is compact, simple in design, light in weight and is easy to manufacture. The hoist may be used with an ordinary welded coil wire chain, rope, or cable, flexible in all planes, to raise and lower the load, thus making the device more convenient to use.

The hoist can be operated with the handle in front or rear position, the chain can be free-wheeled on pocket wheel 6 in either direction with no load, and there is no danger of dropping the load accidentally through inadvertent operation of the device.

Springs 18, 33, and 48 are readily accessible for replacement by removing screw 11, washer 10, and handle 13.

The details of the structure may be varied substantially without departing from the spirit of the invention, and the exclusive use of those modifications of the invention coming within the scope of the claims is contemplated.

What is claimed is:

1. A device of the kind described comprising a rotatably mounted wheel having a peripheral zone for mounting a load supporting element, a ratchet wheel for rotating said load supporting

wheel and with teeth spaced axially from said zone, an operating handle rotatable about a common axis relative to said ratchet wheel, a load pawl and a handle pawl arranged to engage said ratchet teeth, and means for controlling engagement of said pawls with said ratchet teeth to produce step by step rotation of said load supporting wheel in a predetermined direction by operation of said handle.

5 10 2. A device as described in claim 1 including means to disengage both the load pawl and the handle pawl from the ratchet wheel when no load is supported by the load supporting wheel to permit free rotation of the load supporting wheel in either direction.

15 20 3. A device as described in claim 1 including means to permit the load supporting wheel to be rotated freely in either direction when it supports no load, and to prevent rotation of the load supporting wheel, except by operation of said handle, in a direction to lower the load when the load supporting wheel is supporting a load.

25 30 4. A device of the kind described comprising rotatable load supporting and ratchet wheels, flexible means engaging said load supporting wheel and adapted to carry the load, an operating handle arranged to rotate about a common axis relative to said ratchet wheel, a load pawl and a handle pawl arranged to engage said ratchet wheel and positioned out of the plane of said flexible means and said load supporting wheel, and means for controlling engagement of said pawls with said ratchet wheel to produce step by step rotation of said load supporting wheel in a predetermined direction by operation of said handle.

35 40 5. A device of the kind described comprising a housing, a shaft supported by said housing, a wheel having a peripheral zone for mounting a load supporting element, a ratchet wheel having teeth spaced axially from said zone, said wheels being mounted on said shaft and rotatable one by the other, an operating handle rotatable on said shaft, a load pawl supported by the housing 45 and a handle pawl supported by the handle, said pawls being arranged to engage said ratchet teeth, and a cam adapted to disengage said load pawl and said handle pawl alternately from said ratchet teeth while lowering the load.

50 55 6. A device of the kind described comprising a housing, a shaft in said housing, a wheel having a peripheral zone for mounting a load supporting element, a ratchet wheel having teeth spaced axially from said zone, said wheels being mounted on said shaft and rotatable one by the other, an operating handle on said shaft and rotatable relative to said wheels, a load pawl supported by said housing and a handle pawl supported by said handle, said pawls being arranged to engage 60 said ratchet teeth, and means for controlling engagement of said pawls with said ratchet teeth to produce step by step rotation of said load supporting wheel in a predetermined direction by operation of said handle.

65 7. A device of the kind described comprising a housing, a shaft supported rotatably by said housing, a load supporting wheel and a ratchet wheel rigid with said shaft, an operating handle rotatable on said shaft, a load pawl supported by the housing and a handle pawl supported by the handle, said pawls being arranged to engage said ratchet wheel, and a cam adapted to disengage 70 said load pawl and said handle pawl alternately from said ratchet wheel while lowering the load, 75 a trigger on said handle pawl adapted to move

relative thereto, when said trigger engages said cam, without disengaging said handle pawl from said ratchet wheel when said pawl sustains the load, and to move said handle pawl out of contact with said ratchet wheel, when said trigger engages said cam and said pawl does not sustain the load.

8. In combination, a housing, a ratchet wheel having teeth and a load supporting wheel rotatable in said housing, a handle rotatable relative to said ratchet wheel and swingable from an operating range at one side of said housing to an operating range at the opposite side of said housing, a load pawl and a handle pawl engageable with said ratchet teeth, pawl control means having a pawl actuating face, and a member associated with said handle pawl and engageable by said face on said means as said handle moves from one range to the other, said member moving relative to said handle pawl and without disengaging said handle pawl from said ratchet teeth when said handle pawl sustains the load, and said member disengaging said handle pawl from said ratchet teeth when said handle pawl does not sustain the load.

9. In combination, a housing, ratchet and load supporting wheels rotatable in said housing, a handle rotatable relative to said ratchet wheel and movable from an operating range at one side of said housing to an operating range at the opposite side of said housing, a load pawl and a handle pawl engageable with said ratchet wheel, pawl control means having a pawl actuating face, and a member associated with said handle pawl and engageable by said face on said means as

said handle moves from one range to the other, a spring between said handle pawl and member, said spring yielding without disengaging said handle pawl from said ratchet when said handle pawl sustains the load and disengaging said handle pawl from said ratchet when said handle pawl does not sustain the load.

10. A device of the kind described comprising a rotatably mounted wheel having a peripheral zone for mounting a load supporting element, a ratchet wheel for rotating said load supporting wheel and with teeth spaced axially from said zone, an operating handle rotatable relative to said ratchet wheel, a load pawl and a handle pawl arranged to engage said ratchet teeth, and a cam directly engaging and moving said pawls for controlling engagement of said pawls with said ratchet teeth to produce step by step rotation of said load supporting wheel in a predetermined direction by operation of said handle.
